UNITED STATES PATENT OFFICE.

TITUS LANGILLE, OF MAHONE BAY, NOVA SCOTIA, ASSIGNOR OF ONE-HALF
TO BENJAMIN WESTHOVER, OF LUNENBURG, CANADA.

CONSTRUCTION OF SHIPS.

SPECIFICATION forming part of Letters Patent No. 300,714, dated June 17, 1884.

Application filed April 22, 1884. (No model.)

To all whom it may concern:

Be it known that I, TITUS LANGILLE, a subject of the Queen of Great Britain, and a resident of Mahone Bay, in the county of Lunenburg, Province of Nova Scotia, and Dominion of Canada, have invented certain new and useful Improvements in the Construction of Ships; and I do hereby declare that the following is a full, clear, and exact description of the invention, which will enable others skilled in the art to which it appertains to make and use the same, reference being had to the accompanying drawings, which form a part of this specification, and in which—

15 Figure 1 is a longitudinal sectional view through the middle of a vessel having the hold constructed according to my improvement. Fig. 2 is a vertical cross-section of the same on an enlarged scale. Fig. 3 is a plan view of the 20 floor-beams; and Fig. 4 is a detailed view of the flooring, showing the construction of the removable flooring-strips.

Similar letters of reference indicate corresponding parts in all the figures.

25 My invention relates to an improved construction of the holds of vessels, which has for its object to prevent the loss incident to the drainage in cargoes of sugar, molasses, and other goods of a similar nature. In cargoes 30 of this class the loss by drainage on long ocean-voyages averages about ten per cent., as the sugar or molasses which drains from the casks or hogsheads runs to the bottom of the hold, where it mixes with the bilge-water during 35 the passage, and is pumped overboard with it. By my improved construction of the hold, as hereinafter more fully described and claimed, this loss is entirely obviated, and all the drainage is saved in as good condition as the original 40 contents of the casks or hogsheads. This construction also enables vessels to carry cargoes of grain, salt, or other dry and perishable cargoes in a good and perfectly dry condition, without damage from sea-water or 45 bilge-water; and it has this additional advantage, that it adds greatly to the strength of the ship, and, by constructing the same with a water-tight ceiling, makes it impossible for the ship to sink, even if it should spring a leak in 50 the bottom.

In constructing the hold of a vessel accord-

ing to my improvement care must be taken in the first place to calk the vessel carefully and make it tight. The ceiling and inside skin is also carefully calked from the keelson up to 55 the air-streak and made perfectly water-tight, and at the ends of the vessel there are dead-woods and timbers fitted to the keelson, the ends of the ceiling being fitted to those timbers and calked, whereby the fore and aft 60 parts of the vessel are both strengthened and made water-tight.

In the bottom of the hold, impinging at one end upon the keelson A and at right angles thereto, are placed thick planks B, set on edge 65 and extending out to the turn of the bilge. These planks are set at a distance of about twenty-two inches from one another through the length of the hold, the planks being made tapering on their under side, so as to come to a 70 point, C, at the turn of the bilge. They are held in place edgewise by substantial cleats E, which are spiked or otherwise fastened to opposite sides of the keelson, and also by the cross-beams F, which are let into the sides of 75 the planks B, as shown more clearly in Fig. 3, the planks being mortised on their sides to receive the ends of the beams F. Upon these beams rest the removable flooring-planks G, which are spaced apart, so as to leave narrow 80 open spaces H. When the vessel is to be used for shipping grain, salt, or similar merchandise in bulk, the openings H are closed by strips I, the sides of which are beveled, as shown in Fig. 4, to fit the beveled sides of adjacent flooring-planks G. The top of planks B is about three inches above the level of the flooring G, which enables the casks resting on their quarter-hoops upon the ribs formed by the planks B to clear the flooring with their 85 bilge or belly. The planks B are cut away on their under side to form apertures b, through which the drainage that drops down through the slots or openings H in the flooring is permitted to run back to the well K. There may 90 be one or more of these collecting-wells, each consisting of a hollow block sunk down through the ceiling and timbers—one on each side of the keelson—forming basins or reservoirs to receive the drainage, and from which this may 95 be pumped up whenever desired and filled into empty casks which are carried for the purpose. 100

Having thus described my invention, I claim and desire to secure by Letters Patent of the United States—

As an improvement in the construction of ships, the hold constructed with a bottom formed by the parallel cross-timbers B, tapering toward the turn of the bilge on the side of the vessel, set on edge at right angles to the keelson, and having openings b, in combination with the holding-cleats E, cross-timbers F,

flooring G, and removable strips I, constructed and combined substantially as and for the purpose shown and set forth.

In testimony that I claim the foregoing as my own I have hereunto affixed my signature in presence of two witnesses.

TITUS LANGILLE.
